DESIGN FOR A LAPEL BUTTON OR SIMILAR ARTICLE

John P. Hightower, Charleston, W. Va., assignor
to Atlantic Greyhound Corporation, Richmond, Va., a corporation of Virginia

Application October 26, 1945, Serial No. 123,224

Term of patent 14 years

(Cl. D29—2)

To all whom it may concern:

Be it known that I, John P. Hightower, a citizen of the United States, residing at Charleston, in the county of Kanawha and State of West Virginia, have invented a new, original, and ornamental Design for a Lapel Button or Similar Article, of which the following is a specification, reference being had to the accompanying drawing, forming a part thereof.

Fig. 1 is a front elevational view of a lapel button showing my new design, and
Fig. 2 is an edge view thereof in plan.

I claim:

The ornamental design for a lapel button or similar article, as shown.

JOHN P. HIGHTOWER.
